Inventor:

David Williamson

United States Patent Office.

DAVID WILLIAMSON, OF NEW YORK, N. Y., ASSIGNOR TO JAMES WILLIAMSON, OF SAME PLACE; AND SAID JAMES WILLIAMSON ASSIGNS HIS RIGHT TO HIMSELF AND DAVID WILLIAMSON.

Letters Patent No. 87,997, dated March 16, 1869.

IMPROVEMENT IN BREECH-LOADING ARMS.

The Schedule referred to in these Letters Patent and making part of the same.

To all whom it may concern:

Be it known that I, DAVID WILLIAMSON, of the city and State of New York, have invented and made a certain new and useful Improvement in Breech-Loading Fire-Arms; and I do hereby declare the following to be a full, clear, and exact description of the said invention, reference being had to the annexed drawing, making part of this specification, wherein—

Figure 1 is a longitudinal section of the breech and rear portion of the barrel, with the parts in position for firing the gun;

Figure 2 is a similar view with the breech open;

Figure 3 is a plan, with the breech open, and the parts in corresponding position to fig. 2; and

Figure 4 is a cross-section at the line $x x$, fig. 2.

Similar marks of reference denote the same parts.

I employ a breech-block, that is lifted at its rear end by a lever, and slidden back, the front end remaining in the recess at the rear of the barrel, and a retractor is attached to the lower part of the breech-block, at the front end, so as to pull out the cartridge-case entirely clear of the barrel.

In the drawing—

a represents a portion of the rear part of the barrel, and

b is the tongue, extending down the stock, to unite the same with the stock, as usual.

The recess *c*, that is at the rear of and in line with the bore of the gun, is either formed in the barrel itself, or in a metallic breech-piece, screwed upon the rear end of the barrel.

This recess *c* receives the sliding breech-pin *d*, that, when down in place, sets, at its forward end, against the rear of the barrel, and at its back end, against the abutment *e*.

Beneath the breech-pin *d*, and within an undercut, or dovetailed recess in the bottom of the recess *c*, is a sliding cartridge-retractor, *i*, that has a lip at its forward end, to act upon the flange of the metallic cartridge-case *f*, and this retractor *i* is connected, by a slot and screw, 2, or similar means, with the forward under part of the breech-pin, so that the retractor may be moved by said breech-pin, and that the retractor may hold down that end of the breech-pin *d*

when the rear end is lifted above the abutment *e* and the breech slidden back.

I provide grooves and ribs at 3, in the sides of the breech-pin *d*, taking correspondingly-shaped grooves in the metal above the abutment *e* and upper portion of the tongue, or strap *b*, so that the breech-block will be guided by these grooves and ribs as it is slidden back to the position shown in fig. 2.

The upper and rear portion of the breech-block *d* is slotted, for the lever *g* to swing in.

This lever *g* has its fulcrum at *l*, in the portion *b*, which is slotted for its reception, and in this lever *g* is a slot, 5, for the pin *o*, that passes across the rear upper part of the breech-block *d*.

The length of the slot 5 is such, that when the lever *g* is moved into the position shown by red lines in fig. 1, the rear end of the breech-pin *d* will have been raised to the height necessary for the grooves and ribs to coincide, and the pin *o*, coming to the end of the slot 5, the breech cannot be raised any higher, but will be slidden back by the further movement of the lever *g*.

The reverse movement closes the breech, and the spring *m*, acting under the heel 6 of the lever *g*, keeps the parts from swinging open accidentally, or in handling the piece.

What I claim, and desire to secure by Letters Patent, is—

1. The breech-block *d*, provided with the ribs and grooves 3, and fitted to slide back when raised out of the recess *c*, in combination with the lever *g*, slot 5, and pin *o*, substantially as specified, so that the lever *g* communicates to the breech the motions specified.

2. The sliding retractor *i*, within an undercut groove at the bottom of the recess *c*, in combination with the breech-block *d*, for holding down the forward end of said breech-block, as well as withdrawing the cartridge-case, as specified.

In witness whereof, I have hereunto set my signature, this 8th day of May, A. D. 1868.

DAVID WILLIAMSON.
